UNITED STATES PATENT OFFICE.

ABEL KLUGE AND ENEVAL KLUGE, OF ST. PAUL, MINNESOTA, ASSIGNEES TO BRANDT-JEN AND KLUGE, INC., OF ST. PAUL, MINNESOTA, A CORPORATION OF MINNESOTA.

SHEET-DELIVERY MECHANISM.

Application filed April 18, 1923, Serial No. 632,982. Renewed July 16, 1925.

Our invention relates to improvements in mechanism for removing printed sheets from the platen of a printing press.

Its object is to provide an improved pneumatic sheet delivering means including suction grips and an adjustable mounting therefor providing for the selective positioning of said grips on a sheet to be moved.

With the foregoing and other objects in view, which will appear in the following description, the invention resides in the novel combination and arrangement of parts and in the details of construction hereinafter described and claimed.

In the drawings, Fig. 1 is a perspective view of mechanism embodying our invention, the same being shown in connection with a platen press and, Fig. 2 is a fragmentary sectional view illustrating the reach, in detail, also, parts connected therewith.

In the drawings 10 indicates the frame of a printing press, supplied with the usual platen 11 and a carriage A including a tubular support 12 reaching transversely of the frame 10. Our sheet delivery mechanism, now to be specifically described, is mounted on said carriage and moved thereby toward and away from the platen, also elevated and depressed to direct the grips in their cycle of operation.

A tubular reach 13 extending longitudinally of the press is adjustably secured to the support 12 by means of a clamp B. A flexible suction hose 14 connects with the rear end of said reach B, the forward end of the reach being supplied with a head C comprising a plug 15 fitted in the bore of the reach 13 and upper and lower plates 16 and 17 spaced apart and extending forwardly from said plug. Two arms 18 are carried by the reach 13, one end of each arm laps the other between the plates 16 and 17. A bolt 19 reaching through an aperture in the upper plate 16, also through apertures in said arms 18 and threaded at its lower end in the lower plate 17 serves to draw said plates together and clamp the ends of said arms 18 between them. Each arm 18 carries a suction grip 20 slidably adjustable thereon. Each grip 20 is connected through a flexible conduit 21 with a nipple 22 communicating with the bore of the reach 13 and extending from a side of said reach.

The clamp B includes a block 23, having 55 a seat 24 for the reach 13 and a bore 25 therein to receive the support 12. A kerf 26 cut through the rear of the block 23 and into the bore 25 forms upper and lower jaw members 27 and 28. A bolt b formed with an enlarged longitudinally slotted body portion 29, through which the reach 13 extends, is included in the clamp B. The end 29^a of said bolt passes through apertures in the jaw members 27 and 28, the head thereof 60 bearing beneath the lower jaw 28. The threaded end 29^b of said bolt is fitted with a wing-nut 30 and slidably carries a clamping member 31. The tightening of this wing-nut forces the clamping member 31 70 against the reach 13 and said reach against its seat 24 in the block 23. It also pulls the bolt b upward causing the jaws 27 and 28 of the block 23 to grip the support 12. Thus it will be seen that the reach 13 may be 75 adjusted longitudinally of the clamp B and that the clamp itself may be adjusted longitudinally of the support 12 and also angularly thereof.

In removing printed sheets from a platen, 80 it is often desirable to avoid contact between the grips 20 and inked portions of said sheets. Areas not inked and suitable for contact with the grips of delivery mechanism vary greatly according to the nature 85 of the work, size of the sheets and the location thereof on the platen of the press. Any suitable contacting areas for the grips 20 of our improved device are reached by appropriate adjustments. Provision for the 90 placement of the grips 20 in the sheet grasping plane is made by adjusting the block 23 angularly of the support 12, while the longitudinal adjustment of said block on said support suitably locates the reach 13 longitudinally of the platen 11. The reach 13 is suitably located transversely of the platen by adjusting the same longitudinally in its seat 24 in the block 23. After appropriately 95 swinging the arms 18 and sliding the grips 20 thereon to locate said grips in selected gripping positions, the bolt 19 is tightened in the head C and said arms thereby rigidly secured at the desired angles. From the foregoing it will be understood that the 100 grips 20 are not confined to any fixed relation with respect to each other or with respect to sheets to be removed thereby. Either 105

of the grips may be positioned to grasp a sheet at any available unlinked spot within the range of the device.

Changes in the specific form of our invention as herein disclosed, may be made within the scope of what is claimed without departing from the spirit of our invention.

Having described our invention, what we claim as new and desire to protect by Letters Patent is:

1. In a delivery mechanism for removing sheets from the platen of a press, a reach movable toward and away from the platen, said reach having a longitudinal section bore therein, arms on said reach pivotally adjustable independently of each other, a suction grip slidably adjustable on each arm and flexible conduits, each conduit bringing one of said grips into communication with the bore of said reach, the adjustment of the grips on said arms and of said arms on said reach serving to station the grips in various sheet engaging positions.
2. In a delivery mechanism for removing sheets from the platen of a press, a reach movable toward and away from the platen, said reach having a longitudinal suction bore therein, an arm pivotally adjustable on said reach, a suction grip slidably adjustable on said arm and a flexible conduit bringing the bore of said reach into communication with said grip, the adjustment of the grip on said arm and of said arm on said reach serving to station the grip in various sheet engaging positions.
3. In a delivery mechanism for removing sheets from the platen of a press, a reach movable toward and away from the platen, arms independently adjustable on said reach

and grips, one for each arm, each grip being adjustable on its respective arm.

4. In a sheet delivery mechanism, a carriage, a reach adjustable on the carriage, an arm adjustable on the reach and a grip adjustable on the arm, said grip serving to remove sheets from sheet receiving position and adapted, through said adjustments, to be positioned to grasp sheets at various selected points.

5. In a sheet delivery mechanism, a movable reach, an arm adjustable on the reach and a grip for taking sheets from one position and depositing the same in another position, said grip being slidable on said adjustable arm and adapted to engage sheets at various selected points.

6. In a sheet delivery mechanism, a movable reach having a longitudinal suction bore therein, an arm adjustable on said reach, a suction grip adjustably mounted on said arm, and a suction conduit bringing said grip into communication with said bore in the various positions of adjustment of said arm on said reach and in the various positions of adjustment of said grip on said arm.

7. In a sheet delivery mechanism, a movable support, grip carrying means mounted on said support for adjustment about a pivotal axis, and adjustable grips carried by said adjustable means for grasping a sheet at points variously spaced from and angularly related with respect to said pivotal axis.

In testimony whereof, we have signed our names to this specification.
